(57) **CLAIM**

The ornamental design for a seed handling element, as shown and described.

DESCRIPTION

FIG. 1 is a lower, rear, right perspective view of a seed handling element showing my new design;

FIG. 2 is a lower, rear, left perspective view thereof;

FIG. 3 is a lower, front, right perspective view thereof;

FIG. 4 is a rear view thereof;

FIG. 5 is a front view thereof;

FIG. 6 is a top plan view thereof;

FIG. 7 is a bottom plan view thereof;

FIG. 8 is a right side elevational view thereof; and,

FIG. 9 is a left side elevational view thereof.

The broken line representations in the figures show unclaimed environment or boundaries, and thus form no part of the claimed design.

The nature of this product is a component, or portion thereof, used in seed planting machines, such as for facilitating the hand-off between a seed metering device and a seed delivery device.
